MOISTURE SENSING VALVE MEANS
FOR FUSE FILTER

George J. Topol and John G. Vattay, Hamilton, Ontario, Canada, assignors to Bowser, Inc., Cookeville, Tenn., a corporation of Indiana

Filed Oct. 4, 1965, Ser. No. 492,452

7 Claims. (Cl. 210—96)

ABSTRACT OF THE DISCLOSURE

A fuse filter element having a moisture sensitive paper trigger attached to and holding in an open position a poppet valve located at one end of the element. When moisture penetrates the fuse filter the paper trigger tears and releases the poppet valve to move to a closed position at the other end of the element and thereby block further fluid flow.

This invention relates to an improved safety device for filter apparatus and particularly it pertains to a safety device which is responsive to the presence of moisture of a predetermined amount and is adapted to function automatically to terminate operation of the filter under such conditions of contamination.

This invention is related to co-pending application Ser. No. 471,008, filed July 12, 1965, now Patent No. 3,367,503, titled "Fuse Filter With Water Sensitive Valve Closure Trigger," and assigned to the same assignee as the present application.

A filter apparatus has a capability of removing solid and liquid phase contaminants but, in use, such contaminants tend to build up and reduce the efficiency in operation of the apparatus. Should the filter apparatus become sufficiently reduced in efficiency so that it fails to remove contaminants, or should the material being filtered have an excessive contamination which the filter is incapable of removing, then in those instances the filter should be rendered inoperative since it fails to produce a filtered product of the desired purity.

To achieve these results there is incorporated into the filter apparatus a safety device which is intended to operate automatically to terminate operation of the filter. Prior to such operation, however, it is essential that the safety device not interfere with normal operation of the filter and should become operative only at the point where the material being filtered is excessively contaminated or when the filter is itself unduly contaminated. Until such point of excessive contamination, however, it is an important requisite that the safety device be noninterfering with normal operation of filtration.

Accordingly, it is one of the principal objects of the present invention to provide a safety device which will operate reliably to terminate operation of the filter apparatus responsively to excessive contamination of the material being filtered.

It is a further object of the invention to provide a filter apparatus safety device in which the safety device is disposed in a nonturbulent portion of the filter so as not to be responsive to conditions of fluid flow, but on the contrary to be only responsive to conditions of contamination of the fluid undergoing filtration.

It is another object of the present invention to provide a filter cartridge, incorporating a safety device, which can be easily mounted and demounted, by providing novel locating means and nozzle means for directing the flow of filtered fluid through the apparatus after it has passed through the filter element.

It is a further object of the present invention to pro-

2

vide a combination safety device and filter which is operable by combined spring and hydraulic action to effect operation of the safety device to terminate the filter operation under conditions of excessive contamination.

It is a further object of the present invention to provide a safety device which can be designed to operate precisely at a prescribed condition of contamination and thereby achieve a greater useful life of the filter element.

It is an important feature of the present invention that the safety device can be constructed to serve many different size cartridge elements so that, regardless of the cartridge location, or size, the device will operate to terminate filter operation under conditions of excessive contamination.

The present invention incorporates an important feature in the use of a trigger paper which is adapted to operate upon exposure to a predetermined amount of water contamination and which cannot be operated by such other parameters as variations of flow, pressure drop, etc.

The foregoing objects and features of the invention are achieved together with other objects and features which will become apparent from a consideration of the following description which proceeds with reference to the accompanying drawings, wherein:

FIGURE 1 is a side elevation view of a filter assembly having a number of filter elements therein;

FIGURE 2 is a longitudinal section view of a filter element incorporating the present invention therein, and in which the safety device is in a retracted or open position;

FIGURE 3 is an enlarged sectional view of the outlet end of the filter element after the safety device has been operated to terminate flow through the filter element; and

FIGURE 4 is an isometric view of the safety device shown separated from the filter element in FIGURE 2 and prior to its insertion.

Referring now to the drawings, and particularly to FIGURE 1, the filter apparatus designated generally by reference numeral 10, includes a casing 12 which defines an inlet chamber 14 having a plurality of filter cartridges 16 which are disposed between deck plates 18 and 20. The chamber 14 has an upper cover 19 which is retained by lugs 9 having pivot pins 11 which pass through sleeves 15 and are secured thereto by nuts 17, the sleeves 15 being secured to the cover 19 by means of an annular retainer flange 21 welded at 23 and 25 to the cover 19 and sleeve 15, respectively. In this manner, the cover 19 is clamped over the casing 12, with the annular flange 25 engaging the end 27 of the casing 12 about its entire periphery and thereby sealing the chamber 14.

A fluid inlet 22 provides an inflow of fluid indicated by the arrow 24 which enters chamber 14 and thereafter passes through filter cartridges 16, the fluid flow being passed through the interior of the filter cartridge as indicated by the arrows 26 and into outlet chamber 28. Upon entering chamber 28 the filtered fluid passes through a flow guide 32 and through the semicircular openings 30 which are formed in the depending flow guide 32, such flow being then directed out through an outlet port 34 (as indicated by the arrow 36) in end wall 38 which is convexly shaped and is of the same general outline as the upper cover 19. The end wall 38 serves to define chamber 28 together with deck plate 20. Cartridges 16 are mounted at their lower ends within openings 40 in the lower deck plate 20 and the upper ends of the cartridges are retained by locating pins 42 which enter the complementary openings 44 in the upper end of the cartridges, these pins being mounted in upper deck plate 18 which is secured through mounting plate 41 and threaded stems 49 (one of which is shown in FIGURE 1) and nuts 46, 48, 50 to casing 12 through mounting lugs

52. In this manner the cartridge elements 16 are removably mounted within the apparatus.

Referring next to FIGURES 2-4, each filter cartridge 16 is comprised of a filter element 54 having a surrounding cotton sock 56 and the interior of the filter element defines a longitudinal passage 58 having at one end a valve seat 60 provided by a coupling 61 with a shoulder 62 bearing against the end of the filter element, and a cylindrical section 64 which fits within the interior of the passage 58. A second cylindrical section 66 of the coupling 61 is surrounded and is gripped by a soft plastisol nozzle 68 which passes through openings 40 of deck plate 20 (FIGURE 1) and seals such openings as it transfers the filtered fluid into chamber 28. At the other end 70 of the filter element (FIGURE 2) is an end cap 71 which bears against the end 74 of the filter element 54 and is sealed by bonding cement 76. The end cap 71 has a conical recess 77 at the center of which is a socket opening 44 which is formed in tubular section 78, the conical section 77 assisting to locate the cartridge when the pins 42 on upper deck plate 18 enter socket opening 44 to locate the cartridge element in place.

When the cartridge element is mounted the soft plastisol nozzle 68 when entering opening 40 forms a seal so that the fluid passing from chamber 14, radially through the filter element 54 and entering longitudinal passage 58 then passes through the openings 40 in the deck plate and enters chamber 28.

Referring to FIGURE 2, the safety device for terminating operation of the filter element when excessive water contamination occurs, is comprised of a nylon composition poppet 80 having a convexly curved sealing surface 82 which is biased into sealing engagement with the valve seat 60 (FIGURE 3) by a combination of spring and hydraulic forces. The spring force is derived from a helical coil spring 84 which is compressed between shoulder 86 and inner surface 88 of the poppet 80, said poppet being held against the resistance of the compressed spring by a paper trigger 90 which is fastened by a wire 92 to the poppet 80 and by a second wire 94 to the end cap. The paper trigger (FIGURE 4) is of sufficient structural strength to maintain the poppet against the resistance of the compressed spring but it loses its strength when exposed to water so that when water does penetrate the thickness of the filter element and comes into contact with the paper, the force of the compressed spring is sufficient to rupture or tear the paper trigger 90 and the spring 84 is then free to bias the poppet along the interior of the passage 58 and toward the valve seat 60.

Because the velocity of hydraulic fluid increases linearly in the direction toward the valve seat 60 the poppet 80 will be carried in a sealing direction by the hydraulic force, eventually reaching the position shown in FIGURE 3. Actually, the combination of spring force, hydraulic force and the force of gravity (the upper end of FIGURES 2 and 3 of the raised ends of the filter element, FIGURE 1) is such that once the paper trigger 90 tears, the cartridge ceases its filter operation almost immediately. The poppet 80 is proportioned in relation to the diameter of the passage 58 so that it cannot tilt or cock appreciably from its proper position as it moves from retracted into sealing position; even should the poppet be angularly misaligned by a slight amount, this will not seriously detract from a perfect seal. Once the poppet is in sealing position, the flow terminates entirely.

As will be noted in FIGURE 2, the paper trigger 90 is fitted within a tapered recess 95 of the filter element 54 so that a portion of the paper trigger lies close to the outer surface of the filter element and consequently water does not have to penetrate through the entire thickness of the filter element before coming into contact with the paper trigger 90. As a result, the filter operation is terminated by the paper trigger when the fluid undergoing filtration is excessively contaminated and before any portion of such excessively contaminated fluid has had

an opportunity to pass radially through the filter and through outlet 66.

The chambers 14 and 28 are equipped with pressure gauges 98 and 100 so that the pressure drop across the filter can be continuously monitored. In this way the filters can be checked for solid contamination as well as for liquid contamination. In the event that the filters are excessively coated with solid contaminates the pressure drop will increase to an excess amount and this will be used as an indication that operation of the filter apparatus should be terminated and the filter elements replaced.

In order to safeguard the filter cartridges against damage from the incoming fluid 24, there is a baffle 102 (FIGURE 1) which serves as a guard against damage to the filter elements.

In operation the various filter elements are positioned with their nozzles 68 force-fitted into the openings 40 and the upper deck plate 18 with the pins 42 is then inserted in place, the pins 42 entering openings 44 to position the opposite ends of the filter cartridges 16. The concave recesses 77 of the end caps facilitate entry of the pins 42 into the sockets 44. At the start of operation the components of the safety device are positioned as indicated in FIGURES 2 and 4.

25 The fluid flow in the direction indicated by the arrow 24 commences through inlet 22 and past the splash guard 102, entering chamber 14 and the fluid then passes through the filter cartridges 16 (FIGURE 2) and entering longitudinal passage 58 where it travels downwardly and, moving in the direction of the arrows 26 (FIGURE 1), enters chamber 28 and leaves through outlet 34 as indicated by the arrow 36. The pressure differential between the unfiltered fluid in chamber 14 and the filtered fluid in chamber 28 is measured by pressure gauges 98 and 100.

35 Should the fluid undergoing filtration become excessively contaminated by the presence of water, the moisture will penetrate the filter element 54, and, since the inclined notch 95 (FIGURE 2) disposes the paper trigger 90 closer to the outer surface of the cartridge, the trigger will be contacted by the moisture and become sufficiently weakened so that it will be torn by the force of the compressed spring 84, and the spring which is fitted within the skirt 81 will bias the poppet 80 downwardly. Since the hydraulic fluid moves faster within the passage 58 the closer the poppet approaches the seat 60, the poppet will thereby be displaced both by hydraulic force and by the force of spring 84 until the convexly shaped surface 82 is in sealing engagement with the seat 60 terminating further flow through the cartridge. The safety device thus operates to terminate the operation responsively to the presence of excessive water contamination of the material being filtered. At the same time, the safety device does not interfere with normal operation of the filter and the paper trigger 90 is not prone to be torn by any factor other than the presence of excessive moisture because it is located at the uppermost part of the filter cartridge at the point of least turbulence.

60 One of the important features of the present invention is that the safety device is not specifically constructed for any particular size filter cartridge and it is possible to equip any size filter cartridge with the safety device and its operation will be substantially unaffected. As a result, the safety device, while operating in the same way regardless of the size of filter element, will nevertheless be as efficient and operate as reliably to effect termination of the filter regardless of the diameter, or the thickness of filter element 54 or the length of the cartridge.

65 The safety device is not responsive to the presence of a solid contaminant because the cartridge is a fine filter. 70 In overall operation the filter has a high dirt removal efficiency and dirt holding capacity and in addition has a high water separation efficiency with the described positive shutoff action. Because the filtration and water monitoring functions are independent it is possible to arrange a structure for best performance of each distinct function.

It is also an important feature of the present invention that the cartridge does not lose sensitivity at low-flow rates.

Although the present invention has been illustrated and described in connection with a single example embodiment, it will be understood that this is illustrative of the invention and is by no means restrictive thereof. It is reasonably to be expected that those skilled in this art can make numerous revisions and adaptations of the invention to suit individual design requirements and it is intended that such revisions and adaptations will be included within the scope of the following claims as equivalents of the invention.

We claim:

1. In a filter assembly, the combination of: a porous filter element permitting flow of fluid therethrough from the outside of the filter element to the inside thereof, said filter element having a longitudinal internal passage, means forming an outlet port including a valve seat disposed at one end of the longitudinal passage, an end cap forming a sealed enclosure at the opposite end of the passage, a poppet valve proportioned to move through the passage and having a sealing surface corresponding to said valve seat, said poppet valve being normally retained in a position adjacent said end cap, and means constructed and arranged to retain said poppet valve in its initial position adjacent said end cap during normal filter operation, said retaining means constructed of moisture sensitive material of such a nature as to tear and release the poppet valve when exposed to moisture penetrating said filter element so that the poppet valve will be moved into a closed position with the valve seat to terminate the flow of fluid through the filter element. 15
2. In a filter assembly as set forth in claim 1, wherein the poppet valve is provided with a skirt section, and a spring is disposed within the skirt section and positioned to engage the end cap to bias the poppet valve toward the valve seat. 35
3. In a filter assembly as set forth in claim 1, wherein the poppet valve is constructed of a relatively hard inert elastomeric material. 40
4. In a filter assembly, the combination of: a porous

filter element permitting flow of fluid therethrough from the outside of the filter element to the inside thereof, said filter element having a longitudinal internal passage, a poppet valve proportioned to move through the passage and located adjacent one end thereof, mounting means disposed at said one end of the filter element passage to position the poppet valve within said passage and to provide a seal at said one end, outlet means disposed at the other end of the filter element passage, said outlet means including a valve seat, a retaining means constructed of moisture sensitive material, and means for securing said retaining means to the mounting means and to the poppet valve for retaining the poppet valve in its initial position at said one end of the passage, said moisture sensitive retaining means constructed and arranged to tear and release the poppet valve when exposed to moisture penetrating said filter element so that the poppet valve will be moved into engagement with the valve seat to close the passage and thereby terminate the flow of fluid through the filter element.

5. In a filter assembly as set forth in claim 4, wherein the outlet means includes a relatively soft sealable nozzle.

6. In a filter assembly as set forth in claim 4, wherein the mounting means includes a spring for biasing the poppet valve in a sealing direction. 25

7. In a filter assembly as set forth in claim 4, wherein the mounting means includes a tubular element projecting into the passage for facilitating the alignment of the poppet valve. 30
